UNITED STATES PATENT OFFICE.

MOSES S. DEARBORN, OF OAKLAND, CALIFORNIA.

MITER BOX.

Application filed July 17, 1926. Serial No. 123,139.

This invention relates to a miter box, and is designed primarily as an improvement upon the construction of miter box disclosed by Letters Patent 1,547,034 granted 5 to me July 21, 1925, and the invention has for its object to provide, in a manner as hereinafter set forth, a simplified construction of miter box with means to enable a saw to be held in a vertically inclined plane 10 while cutting diagonally across an object, so as to cut angles in two directions at the same time and further whereby the saw will be effectively maintained in its various adjustments and further whereby the saw adjustments can be conveniently had when occasion requires.

Further objects of the invention are to provide, in a manner as hereinafter set forth, a miter box which is comparatively simple 20 in its construction and arrangement, strong, durable, compact, thoroughly efficient and convenient in its use, readily adjustable, and comparatively inexpensive to manufacture.

With the foregoing and other objects in view, the invention consists of the novel construction, combination and arrangement of parts, as hereinafter more specifically described and illustrated in the accompanying drawings wherein is shown an embodiment 30 of the invention, but it is to be understood that changes, variations and modifications can be resorted to which fall within the scope of the claims hereunto appended.

In the drawings wherein like reference 35 characters denote corresponding parts throughout the several views:

Figure 1 is a top plan view of a miter box in accordance with this invention.

Figure 2 is a sectional elevation thereof 40 looking towards one end thereof.

Figure 3 is a front elevation of a miter box in accordance with this invention.

Figure 4 is a section on line 4-4, Figure 2.

Figure 5 is a section on line 5-5, Figure 2.

Referring to the drawings in detail, a miter box in accordance with this invention includes a table or base comprising a rectangular body portion 1 formed at its rear, centrally thereof, with a semi-circular extension 18. The body portion at its rear is furthermore formed with a pair of lengthwise opposed, spaced vertically extending supports 4 for a pair of slides to be herein-after referred to. Each support is formed 50 with a vertically disposed or rather perpendicular outer end edge and an inclined

inner end edge. The inclined inner end edge of each support 4 inclines outwardly from the bottom to the top of the support. The inclined inner end edge of each support is 60 indicated at 6. The outer end edge of each of the supports is flush with an end edge of the body portion 1.

Secured to the upper face of the body portion 1, is a pair of spaced wooden strips 65 9, which have their outer end edges flush with the end edges of the body portion 1. The holdfast devices for securing the wooden strips 9 to the body portion 1 are indicated at 10 and 11. The inner end edge of each 70 strip 9 is inclined oppositely from near the rear to the front and rear edges of the strip and in a manner whereby the front edge will be of less length than the rear edge. The inclined parts of the inner end edge of 75 each of the strips 9 are indicated at 15, 16. The inner end edges of the strips are oppositely disposed with respect to each other.

Secured to the lower face of the body portion 1, at each end thereof, is an inverted 80 yoke-shaped support 12, provided with oppositely extending flanges 13 formed with apertures 14 for the passage of hold fast devices to fixedly secure the supports upon a bench or table. The supports 12 are secured to the body portion 1 by the hold fast devices 11.

The inclined inner end portion 15 of each strip 9 is of greater length than the inclined inner end portion 16 thereof. The 90 portions 15 and 16 of one strip 9 are oppositely disposed with respect to the portions 15 and 16 of the other strip 9.

Secured to the lower face of the body portion 1, centrally thereof and projecting from the front side edge of the latter is a segmental shaped plate 17. Hold fast devices 19 are employed for securing the plate 17 in position. The projecting portion of the plate 17 is indicated at 20 and rabbeted on 100 its lower face, as indicated at 22 and against which is secured a packing strip 23 which is coextensive with said portion 20.

The body portion 1, at the point of joinder thereof with the extension 18 and at its transverse center, is provided with a countersunk opening 24 and a depending boss 25 which registers with the opening 24. Secured to the body portion 1 and depending through the opening 24 is a pivot 26 for a 110 purpose to be presently referred to.

Secured to the upper face of this project-

ing portion 20 of the plate 17, as well as being coextensive therewith, is a scale carrying member 27.

The device includes an adjustable combined saw guide and carrier which is of inverted yoke shape and formed of two sections 28 and 29. The section 29 at its rear is formed with an extension 30 and a lug 31, the former being arranged above the latter and projecting rearwardly therefrom. The section 29 is of materially greater length than the section 28 and projects rearwardly from the latter. The sections 28 and 29 at their forward ends are flush 15 with each other and the section 28 is detachably connected to the section 29 by a plurality of hold fast devices 32.

The upper part of the inner faces of the sections 28, 29 are provided with grooves 20 33, 34 respectively which oppose each other and in which is adapted to slide a reinforcement 35 at the top of the saw blade 36, and such reinforcement 35 may be an extension 25 from the saw handle 37. The section 29 has fixed to the outer sides thereof a collar 38 and below the collar 38 a guide member 39. Vertically shiftable in the collar 38 and extending through the guide 39 is a saw depth gauge 40 which is of a length to depend below the guide 39 and to seat on the extension 18 of the plate 17, see Figure 2. The gauge 40 is provided with graduations or a scale 40' and is adjustably connected to the combined saw guide and carrier by a set screw 38'.

Associated with the combined saw guide and carrier is a coupling mechanism for connecting it to a means for adjusting the combined saw guide and carrier in a vertical inclined plane and the said means is indicated generally by the reference character 41. The coupling mechanism includes a pair of superposed links 42, 43; the former is pivotally connected as 44 to the adjusting means 41 and also pivotally connected as at 45 to the extension 30. The link 43 is pivotally connected as at 46 to the adjusting means 41 and also pivotally connected as at 47 to the lug 31. The construction and arrangement of the coupling mechanism permits of the links 42 and 43 to be swung on the pivots 44 and 46 to a vertical position carrying the combined saw guide and carrier therewith whereby the latter can be held in elevated position and suspended at right angles with respect to the said means 42. The combined guide and carrier can also be swung on the pivots 45 and 47.

The means 41 for adjusting the combined saw guide and carrier to a vertical inclined plane comprises a pivoted pointer 48, formed at one side with a forwardly extending bracket arm 49 to which are attached the pivots 44 and 46. The pivot for the pointer 48 is indicated at 49'. The lower portion

of the arm 49 projects forwardly with respect to the upper portion thereof whereby the pivot 46 is positioned in advance of the pivot 44. The lower portion of the arm 49 carries a support 49' for the link 43. Associated with the pointer 48, for the purpose of shifting the same, is an angle shaped arm 51 provided with an opening 52 formed with a threaded wall. The arm 51 extends rearwardly from the upper end of the pointer 48. Arranged rearwardly of the pointer 48 is a quadrant shaped plate 53, in the bottom of which, is mounted the pivot 49'. The plate 53 has its forward face at its top provided with graduations 54 which associate with the pointer 48 to obtain the desired adjustment of the combined saw guide and carrier when adjusting the latter to a vertically inclined plane. The arm 51 overlaps the top of the plate 53 and carries a binding screw 55, having threaded engagement with the wall of the opening 52 and said screw 55 abuts against the rear face of the plate 53 for maintaining the pointer 48 in its adjusted position with respect to one 90 of the graduations 54.

The device further includes means for adjusting the combined saw guide and carrier to various angular positions with respect to the table top or base and the same means consists of a lever arm 56, which at its rear end is formed integral with the lower end of the plate 53. The lever arm 56 at a point between its transverse center and forward end is shiftable mounted on the pivot 26. The upper face of the forward end of the lever arm 56 is provided with a rearwardly directed angle shaped projection 57 which overlaps the forward portion 20 of the plate 17. The lever arm 56 at its forward end is provided with an opening 58 having a threaded wall and which engages a set screw 59 which when adjusted engages the portion 20 of the plate 17 and maintains the lever arm 56 in its adjusted position. When the combined saw guide and carrier is angularly adjusted with respect to the sections 1, 2 and 3 of the table top the links 42, 43 and the means 41 are bodily carried therewith.

The device further includes an adjustable guide mechanism employed in connection with the combined saw guide and carrier for the purpose of guiding the latter in the position to which it has been adjusted and also to permit of the same to fall away from a vertical plane. The said guide mechanism comprises a pair of vertically disposed back-rest extension slides, between which the combined saw guide and carrier passes. The slides are manually shifted to the desired extent and when so shifted are locked from movement. The slides are indicated at 60, 61 and the inner end of each is beveled to conform to the inclination of the portion 16 at the inner end of a strip 9. The slides 60

and 61, at their upper portions, are bent as at 62 to overlap the upper edges of the supports 4 formed on the body portion 1 of the table top. Each slide has fixed thereto a 5 clamping screw 63, which extends through the bent portion 62 thereof and engages the rear face of a support 4 for fixedly securing the slide in set position. The slides are capable of being shifted outwardly and in 10 wardly with respect to the supports 4 for supporting the saw guide when the latter is adjusted to hold the saw in a direction in which the cut is to be made.

The construction and arrangement of parts, 15 as hereinbefore set forth, will enable a saw to be held in a vertically inclined plane while cutting diagonally across an object, so as to cut angles in two directions at the same time, and further whereby the saw will be fixedly 20 maintained in its various adjustments, therefore it is thought that the many advantages of a miter box, in accordance with this invention, can be readily understood, and although the preferred embodiment of the invention 25 is as illustrated and described, yet it is to be understood that changes in the details of construction can be had which will fall within the scope of the invention as claimed.

What I claim is:

30 1. In a miter box, a table provided at its rear with a pair of lengthwise opposed, spaced upright supports having oppositely extending inclined inner ends, a pair of lengthwise opposed, spaced independently 35 adjustable, vertically disposed, shiftable members positioned against the front and

overhanging the top of said supports and providing means to permit a combined saw guide and carrier element to tilt from a vertical plane and for supporting said element 40 in tilted position, and means carried at the rear of the overhanging part of each of said members for fixedly securing the member in set position.

2. A miter box constructed in accordance 45 with claim 1, said supports and said members having oppositely disposed bevelled inner ends, the bevelled inner ends of the supports corresponding to the bevelled inner ends of 50 said members.

3. In a miter box an adjusting mechanism 55 for a tilttable and diagonally adjustable combined saw blade guide and carrier element, said mechanism including combined supporting and coupling means for said element consisting of a bracket having its lower part of greater length than its upper part, an upper link for pivotal connection with said element and pivotally connected to said upper part, a lower link for pivotal connection 60 with said element and pivotally connected to said lower part, and a support for said lower link, said support carried by said lower part outwardly with respect to the pivot between the lower link and lower part. 65

4. In a miter box constructed in accordance with claim 3, said lower link projecting beyond the outer end of the upper link.

In testimony whereof, I affix my signature hereto.

MOSES S. DEARBORN.
